UNITED STATES PATENT OFFICE.

JOHN M. HOUGHTON, OF WORCESTER, MASSACHUSETTS, ASSIGNOR TO HOUGHTON MANUFACTURING COMPANY, A CORPORATION OF MASSACHUSETTS.

DOFFING-RAIL LOCK FOR SPINNING FRAMES.

1,411,276.

Specification of Letters Patent.

Patented Apr. 4, 1922.

Application filed May 28, 1920. Serial No. 384,805.

To all whom it may concern:

Be it known that I, JOHN M. HOUGHTON, a citizen of the United States, residing at Worcester, in the county of Worcester and 5 State of Massachusetts, have invented a new and useful Doffing-Rail Lock for Spinning Frames, of which the following is a specification.

This invention relates to a device for automatically locking the doffing rail of a 10 spinning frame in raised balanced position and preventing it from being raised too far. The principal objects thereof are to provide a device for this purpose of an extremely 15 simple and inexpensive construction, and with no parts that are likely to get out of order or that will be in the way of the proper operation of the frame; and to provide a construction which can be unlocked 20 readily by a very simple motion to allow the doffing rail to be turned down to its normal horizontal position.

Reference is to be had to the accompanying drawings in which—

25 Fig. 1 is a plan of a part of a spinning frame thread board showing a preferred embodiment of this invention applied thereto;

Fig. 2 is a front elevation of the same with parts broken away to show interior 30 construction;

Fig. 3 is a side view with parts shown in section on the line 3—3 of Fig. 1, and in normal horizontal position;

Fig. 4 is a similar view showing the position of the parts when locked;

Fig. 5 is a section on the line 5—5 of Fig. 2;

Fig. 6 is a bottom plan view of a bracket for supporting the locking member, and

40 Fig. 7 is a front elevation thereof.

Difficulty is encountered in operating spinning frames from the fact that, when the doffing rail is to be raised for doffing, the operator is apt to turn it up to its extreme 45 position. This brings the yarn into a nearly straight path from the bobbins to the drawing rolls. Then when the rail is turned down again the yarn is directed in an angular course which stretches it and has a tendency to cause it to break.

50 This invention is designed to overcome that difficulty and at the same time do it in an extremely simple manner and without complicated or expensive attachments.

The invention is shown as applied to a 55 spinning frame having a doffing rail 10 pivoted on studs 11 carried by brackets 12 some distance in front of the roller beam 9 so that it can move from the horizontal operating position shown in Fig. 3 to the elevated position for doffing shown in Fig. 4.

This invention is shown in a form involving a single locking device for the entire doffing rail and comprising a bracket 15 usually formed of sheet metal and attached to the bottom of the doffing rail. This bracket is provided with depending lugs 16 which are perforated to provide bearings separated from each other for a pivot pin 17 which pivotally supports the locking member 18. This is made from a plain flat stamping of sheet metal and has a depending portion 19 provided with a notch 20 at the rear and with an inclined surface 21 at the front. It is also provided with a handle 22 which also constitutes an operating weight as will appear.

The locking device comprises another element in the form of a sheet metal stamping 24 secured to the front of the roller beam 80 adjustably by means of a bolt 25 or the like passing through a slot 26 with which it is provided in its vertical or main portion. It also has a slanting projection 27 extending from the main portion and provided with a 85 perforation 28 for receiving the lower guiding end 23 of the pivoted locking member.

In operation when the parts are in normal position the lower guide 23 on the bottom of the locking member rests in the perforation 90 28 and holds the member in its forward position as shown in Fig. 3. It will be observed that the entire weight of this locking member is on one side of the pivot pin 17 and consequently this weight tends to move 95 it backwardly about its pivot. The projecting handle and weight 22 provide a material weight for tending to swing it back by gravity, and therefore when the doffing rail 10 is turned upwardly on its pivot, from any 100 point along it, its inner end will swing down and bring down with it the pivot pin 17. This lowers the locking member sufficiently so that the notch 20 will come into the perforation 28. Immediately upon that 105 change in position the weight of the part 22 forces the member 18 to swing backward by gravity and bring the notch to the end of

the slot or perforation 28 as indicated in Fig. 4. This locks the doffing rail in this balanced position which is the natural position to which a careful operator would turn it for doffing. The lock prevents the careless operator turning it up higher. In the form illustrated the locking member is not locked rigidly against all motion because it can be moved back and forth slightly on its pivot. 10 But it cannot be lowered beyond the point indicated in Fig. 4 because of the slanting nature of the projection 27. The slight swinging motion of the parts will always bring the notch 20 back to the rear of the 15 slot 28. Gravity acts to keep it there as will be seen.

It is not possible therefore to raise the thread board too far and then run the risk of breaking the yarn when it is lowered 20 again.

In order to turn it down, it is necessary to touch the locking member and raise the handle 22. That action in itself brings the notch 20 up out of the slot 28 so that it will 25 no longer lock by gravity because the force applied to the handle 22 slightly raises the pivot 17 and brings the notch up so that it cannot lock again by gravity until it is lowered. Now the operator can restore the 30 doffing rail to its horizontal position as shown in Fig. 3.

Although I have illustrated and described only a single form of the invention, I am aware of the fact that modifications can be 35 made therein by persons skilled in the art without departing from the scope of the invention as expressed in the claims. Therefore I do not wish to be limited to all the details of construction herein shown and 40 described, but what I do claim is:—

1. The combination with a pivoted doffing rail for a spinning frame of means movable therewith for automatically and positively locking it against further upward 45 motion upon its being moved to a raised position for doffing in which it is substantially balanced on its pivots.

2. The combination with a doffing rail pivoted on an axis near its front edge, of a 50 slotted plate located below it, and a locking member pivotally connected with the doffing rail and having a notch provided with abrupt opposite edges for engaging both sides of said plate and locking the doffing

rail in balanced position against motion in both directions.

3. The combination with a tilting doffing rail, of a pivot mounted thereon behind the axis on which it turns, a locking member pivotally depending from said pivot, and 60 stationary means below the doffing rail adapted to be engaged by the locking member to lock the doffing rail automatically whenever it is raised to a balanced position.

4. The combination with a pivoted doffing rail, of a pivoted locking member having an arm projecting forwardly therefrom constituting means for operating it by the force of gravity and also constituting a weight for holding said member in locking 65 position, and stationary means below the doffing rail adapted to be engaged by the locking member to lock the doffing rail automatically whenever it is raised to its balanced position.

5. The combination with a tilting doffing rail, of a slotted plate located below it, and a locking member pivotally connected with the doffing rail for engaging said plate and locking the doffing rail in raised position, 80 said locking member consisting of a flat piece of sheet metal having a forwardly projecting weighted arm for manipulating it.

6. The combination with a pivoted doffing rail for a spinning frame, of a gravity 85 actuated lock for holding it in its upwardly turned position for doffing, comprising a freely depending member having an operating arm projecting forwardly and adapted when lifted to unlock the device and initiate 90 the return of the doffing rail to a horizontal position.

7. The combination with a tilting doffing rail for a spinning frame, of means for automatically locking it in raised position, 95 said locking device comprising a member having a passage therein and a flat piece of sheet metal pivotally depending from the rear edge of the doffing rail and having a notch in its rear side above its lower end for engaging in said passage, and having 100 a guide extending below said notch and provided with a slanting front surface just above said member.

In testimony whereof I have hereunto 105 affixed my signature.

JOHN M. HOUGHTON.
